THE NORRIS PETERS CO., PHOTO-LITHO., WASHINGTON, D. C.

UNITED STATES PATENT OFFICE.

LYMAN CORNWELL, OF DE BEQUE, COLORADO.

KEYLESS LOCK FOR AUTOMOBILES.

1,193,360.

Specification of Letters Patent. Patented Aug. 1, 1916.

Application filed April 21, 1916. Serial No. 92,688.

To all whom it may concern:

Be it known that I, LYMAN CORNWELL, a citizen of the United States, residing at De Beque, in the county of Mesa and State 5 of Colorado, have invented certain new and useful Improvements in Keyless Locks for Automobiles; and I do hereby declare the following to be a full, clear, and exact description of the invention, such as will enable 10 others skilled in the art to which it appertains to make and use the same.

This invention relates to a keyless lock for automobiles and more particular to a combination lock adapted to be connected to 15 the coil box and switch of an automobile, to prevent the switch from being closed to complete the circuit to the coil or coils of the coil box by an unauthorized person or a person not familiar with the combination of 20 the lock, preventing the engine of the automobile from being started.

Another object of the invention is to provide a casing secured to the front wall of the coil box and provided with a central 25 shaft operatively connected to the coil box switch and having a combination means operatively connected therewith to prevent rotation of the shaft until the proper combination has been operated.

30 Another object of the invention is to provide a disk on the shaft adapted to be engaged and held by a plurality of arms which have push buttons connected thereto, which must be pushed to free the disk so that the 35 shaft may be rotated to operate the coil box switch.

A further object of this invention is to provide means connected to the arms for normally holding some of the arms into an 40 engagement with the disk and for normally holding the other arms from an engagement with the disk to make it necessary to press the correct button to the arms which are normally in an engagement with the disk to 45 free said disk and if one of the other buttons is pressed that is connected to the arms which are not in an engagement with the disk, said arms will be forced into an engagement with the disk and hold said disk 50 against rotation providing the correct buttons are pushed or operated.

A still further object of this invention is the provision of a keyless lock for automobiles of the above stated character, which 55 shall be simple, durable and efficient, and

which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a front elevation partly in section, of a keyless lock for automobiles, 70 constructed in accordance with my invention, Fig. 2 is a longitudinal sectional view of the same illustrating the means of locking the central shaft against rotation, and Fig. 3 is a detail sectional view of the switch 75 on the coil box.

Referring in detail to the drawing, the numeral 1 indicates a portion of a coil box, which may be of any desired construction having a recess 2 in the center thereof, in 80 which is rotatably mounted a switch 3, consisting of a shank 4, having oppositely disposed arms 5 secured thereon which are adapted to be moved into an engagement with contact points 6 to close an electrical 85 circuit through coils not shown that are usually mounted in the coil box 1. The shank 4 is provided with its end squared as illustrated at 7 to receive a means or key for operating the switch 3, providing a coil box 90 switch of a well known construction and to which my invention is adapted to be applied.

A circular base 8 is secured to the front wall of the coil box 1 by means of bolts or other suitable means and is provided with 95 a central opening. A circular cover 9 having an angular flange 10 formed thereon is bolted or otherwise detachably secured to the base 8 and is provided with a central depression 11, having an opening therein for 100 receiving a central shaft 12 which extends through the opening in the base 8 and is provided with its end recessed and squared to receive the squared end 7 of the shank 4 of the switch 3. A suitable collar is 105 formed on the shaft 12 and adapted to engage the base 8 within the cover to limit the movement of the shaft 12 in the direction of the switch 3. A pin is detachably secured to the shaft 12 within the recess 2 110

of the coil box 1 to provide means whereby the shaft 12 may be withdrawn from the base 8 by removing said pin. A suitable handle 12' is formed on the outer end of the 5 shaft 12 and located within the depression 11 to provide means whereby said shaft 12 may be rotated to operate the switch 3. Secured to the shaft 12 and within the cover 9 is a circular disk 13 provided with a plurality 10 of openings 14 arranged in circular formation, to be engaged by a plurality of locking arms, which will be hereinafter more fully described. The cover 9 is provided with a plurality of depressions 15 arranged 15 in circular formation and provided with openings therein to slidably receive push buttons 16 which are pivotally secured to the arms heretofore mentioned.

Secured to the base 8 and arranged in 20 circular formation, are a plurality of brackets 17, which are provided with oppositely disposed extensions 18. Formed on the ends of each of the extensions 18 are a pair of relatively spaced plates 19 and 20 which are provided with alining apertures therein. Secured to the base 8 and arranged in circular formation are a plurality of casings 21 which are provided with their free ends closed by detachable caps 22 and 30 are each provided with an elongated slot intermediate their ends and have positioned therein coil springs 23 and plugs 24.

The locking arms heretofore mentioned are each provided on one of their ends with 35 lugs 25 which are adapted to be received within the openings 14 of the circular disk 13 on the central shaft 12. Some of these locking arms are adapted to be normally in engagement with the circular disk 13 and the other arms normally held from an engagement 40 with the disk 13 and to better describe my invention, I am referring to the arms which are normally in engagement with the disk 13 by the numeral 26 and the arms 45 which are normally away from an engagement with the disk by the numeral 27. The arms 26 which are normally in engagement with the disk 13 are pivotally secured between the pair of relatively spaced plates 19 50 upon the brackets 17 by means of pins 28 passing through the alining apertures therein. The ends of the arms are adapted to extend into the cylindrical casings 21 and be interposed between the springs 23 and 55 the plugs 24. The springs which engage the arms 26 are positioned to bear against the detachable caps 22 and the ends of the arms and the plugs engage the ends of the arms and the base 8 to normally urge said 60 arms into an engagement with the circular plate 13. The arms 27 which are normally held from an engagement with the plate 13 are pivotally secured between the relatively spaced plates 20 of the brackets 17 by means 65 of pins 29 and the ends of the arms adapted

to extend within the cylindrical casings 21 between the springs 23 and plugs 24. The casings 21 which receive the ends of the arms 27 have the springs interposed between the ends of the arms and the base 8 to normally hold the lugs 25 upon the arms 26 from an engagement with the openings 14 in the circular disk 13. These arms 27 being limited in their movement within the cylindrical casings 21 by the plugs 24 which 75 are positioned between the detachable caps 22 and the ends of the arms 27.

In order to operate the switch 3 to the coil box 1, the push buttons 15 which are pivotally connected to the operating arms 26 must all be pushed inwardly to raise the lugs 25 from engagement with the openings 14 within the circular disk 13 and held in this position until the switch 3 has been properly operated by rotating the central 85 shaft 12 by handle 12'. If a person is not familiar with the proper buttons to push to free the shaft 12 said person is liable to operate one of the push buttons which is connected to the arms 27 and in this case, 90 the arms 27 will be forced to engage the plate 13 and hold said plate 13 against rotation and prevent the switch from being operated, providing the buttons to the operating arms 26 are correctly operated, providing 95 a combination which cannot be operated unless the person is familiar with the exact push button to operate.

While I have shown and described the preferred embodiment of my invention, it 100 will be understood that minor changes in construction, combination and arrangement of parts may be made without departing from the spirit and scope of the invention as claimed.

Having thus described my invention, what I claim is:

1. A keyless lock comprising a casing, a central shaft journaled in said casing, a circular disk secured to the shaft within the 110 casing and provided with a plurality of openings arranged in circular formation, a plurality of brackets secured within the casing and arranged in circular formation, locking arms pivotally secured to said 115 brackets, lugs formed on the ends of said arms, means for holding some of the lugs within the openings of the disk, and means for holding the lugs on the other arms from engagement with the disk, and push buttons 120 pivotally connected to the arms for moving the arms from engagement with the disk to free the shaft.

2. A keyless lock comprising a casing, a central shaft extending through said casing, a circular disk secured to said shaft and provided with a plurality of openings arranged in circular formation, a plurality of brackets secured within the casing and arranged in circular formation, arms secured 125

- to said brackets, lugs formed on said arms, cylindrical casings secured within the casing and arranged in circular formation, means mounted within some of the cylindrical casings to normally hold the lugs on some of the arms into engagement with the openings of the circular disk, and means mounted within the other circular casings for normally holding the lugs on the other arms from engagement with the circular disk, and push buttons pivotally secured to the arms for operating said arms.
3. A keyless lock comprising a base, a cover secured to said base, a central shaft extending through the cover and base, a circular disk secured to said shaft and provided with a plurality of openings arranged in circular formation, a plurality of brackets secured to the base and arranged in circular formation, extensions formed on the brackets, a pair of relatively spaced plates formed on the ends of the extensions, arms pivotally secured between the pair of relatively spaced plates of each bracket, lugs formed on the ends of said arms, cylindrical casings secured to the base and provided with slots intermediate their ends to receive the ends of the arms, springs mounted in some of the cylindrical casings to bear against the base and the ends of the arms to hold said arms normally from an engagement with the disk, and means mounted in the lower ends of last mentioned cylindrical casings to limit the movement of the arms, springs mounted in the other cylindrical casing and bearing against the ends of the cylindrical casing and the ends of the arms to normally hold said arms in engagement with the disk, and means mounted in the other end of the last mentioned cylindrical casings to form a stop for the arms, and push buttons connected to the arms for freeing the arms from engagement with the disk.
- 45 4. A keyless lock comprising a base, a cover provided with an angular flange de-
- tachably secured to the base, said cover provided with a central depression having an opening therein, a central shaft extending through the opening and base, a handle 50 formed on said shaft, and located within the central depression, a disk secured to said shaft and provided with a plurality of openings therein, brackets secured to the base, arms pivotally secured to said brackets, lugs 55 formed on the arms, means connected to some of said arms for holding the lugs on these arms into engagement with the disk, means connected with the other arms for holding the lugs thereon from engagement 60 with the disk, and means connected with the arms for operating said arms to free the shaft.
5. A keyless lock comprising a base, a cover provided with an angular flange de- 65 tachably secured to the base, said cover provided with a central depression and having an opening therein, a central shaft extending through the opening in the depression and the base, brackets secured to 70 the base, a disk secured to the shaft, and provided with a plurality of openings therein, arms secured to said brackets, lugs formed on said arms, means for normally holding the lugs of some of said arms into engagement 75 with the disk, means for normally holding the other arms from engagement with the disk, said cover provided with a plurality of circularly arranged depressions having openings therein, push buttons slidably mounted within the openings of last mentioned depression and pivotally connected to the arms for moving said arms from engagement with the disk to free the shaft.
- 85

In testimony whereof I affix my signature in presence of two witnesses.

LYMAN CORNWELL.
